UNITED STATES PATENT OFFICE

ELBERON D. SMITH, OF BROOKLYN, NEW YORK, ASSIGNOR TO AMERICAN MACHINE & FOUNDRY COMPANY, A CORPORATION OF NEW JERSEY

SAFETY DEVICE FOR CIGARETTE CUT-OFFS

Application filed August 21, 1931. Serial No. 558,546.

This invention relates to an improvement in cigarette cutoffs particularly to safety devices for cutoffs of the general type disclosed in application Serial No. 531,399, filed February 4th, 1931, to R. E. Rundell. Cigarette cutoffs of this type while giving excellent results at the high speeds for which they are intended are injured now and then due to nails or other foreign objects in the cigarette rod. When this occurs, the tendency is to strip the gears driving the cutoff disk since these gears are made rather light to avoid unbalanced or counterbalanced weight and resulting vibration and are geared rather high to get a quick smooth cut, necessitating an expensive repair and a considerable loss of production.

Accordingly, a principal object of the present invention is to eliminate so far as possible any injury from such obstructions or where that is not possible, to confine such injuries to the spoiling of an inexpensive and quickly replaced blade, and to do this without appreciably complicating the machine or appreciably adding to the unbalanced weight on constructions in which the blade driving means has bodily movement on a rotating carrier. To this end it is an object to provide a simple, light and effective clutch device for permitting slipping of the blade relative to its driving means. With these and other objects not specifically mentioned in view the invention consists in certain constructions and combinations which will be hereinafter fully described and then specifically set forth in the claims hereunto appended.

In the accompanying drawing, which forms a part of this specification and in which like characters of reference indicate the same or like parts, Fig. 1 is a sectional side elevation of a cigarette cut-off illustrating the invention; Fig. 2 is an end elevation of the device shown in Fig. 1.

In carrying the invention into effect, there

is provided a cigarette cut-off having in combination a disk blade, a rotatable mount for supporting and driving said blade, a gear drive for positively rotating said blade and means on said mount for frictionally gripping said disk to permit slipping of the blade without injuring the gear drive when the blade meets an abnormal obstruction. In the best constructions, this rotatable mount is supported on a revolving carrier for orbital movement about the axis of the carrier. Preferably said means include a friction clutch between the gear drive and the blade which the friction means in the best form include a collar on the mount engaging on one side of the blade and a spring washer on the other side of the blade. The various means referred to may be varied widely in construction within the scope of the claims, for the particular device selected to illustrate the invention is but one of many possible concrete embodiments of the same. The invention therefore is not to be restricted to the precise details of the structure shown and described.

Referring to the drawing, a rotating knife carrier disk 5 is illustrated which is mounted on a shaft 6 driven from the main drive of the cigarette machine. The disk 5 has a slidably supported carrier head 7 supporting on a rotatable mount or spindle 8 the circular knife blade 9. The knife spindle 8 is driven from a spiral gear 10 of light construction, meshing with a spiral gear 11 slidably mounted on the square end 12 of a shaft 13. The latter carries a bevel gear 14 which, by the rotating of disk 5 travels about a stationary bevel gear 15 fastened to the flange of cut-off housing 16. The circular knife 9 is gripped by a flat peripheral portion of a dished spring disk or washer 17, equipped with radial slots 18, and a collar 19 mounted on knife shaft 8. Spring disk 17 is fastened to shaft 8 by clamp nut 20 and collar 21. Holding the rotating circular knife 9 by friction created by spring

disk 17, has the advantage of preventing breakage of the lightly constructed knife driving mechanism. If the rotating circular knife 9 in cutting the continuously moving cigarette rod C should strike any foreign matter such as nails, pins, etc., which fall occasionally into the tobacco, the knife 9 can be stopped from rotating while the driving mechanism is still turning and without danger of breaking the gearing.

The continuously moving cigarette rod C is guided towards the rotating knife 9 by means of a mouthpiece 22 and then cut in the desired lengths of the cigarettes between 15 mouthpiece 22 and ledger plate 23.

What is claimed is:

1. A cigarette cutoff having in combination a disk blade, a rotatable mount for supporting and driving said blade, a gear drive for positively rotating said mount, and means on said mount for frictionally gripping said disk to permit slipping of the blade without injuring the gear drive when the blade meets an abnormal obstruction.

2. A cigarette cutoff having in combination a disk blade, a rotatable mount for supporting and driving said blade, a gear drive for positively rotating said mount, means on said mount for frictionally gripping said disk to permit slipping of the blade without injuring the gear drive when the blade meets an abnormal obstruction, and a revolving carrier supporting said mount for orbital movement about the axis of the carrier said carrier being provided with a slidably supported carrier head supporting said mount, and said gear drive including a gear on said mount, a shaft on said carrier, a gear slidably mounted on one end of said shaft, a bevel gear fixed on 30 the other end of said shaft, and a stationary bevel gear meshing with the bevel gear fixed on said shaft.

3. A cigarette cutoff having in combination a disk blade, a rotatable mount for supporting driving said blade, a gear drive for positively rotating said mount, means on said mount for frictionally gripping said disk to permit slipping of the blade without injuring the gear drive when the blade meets an abnormal obstruction, said means including a collar on the mount located on one side of the blade and a spring washer on the other side of the blade.

4. A cigarette cutoff having in combination 55 a disk blade, a rotatable mount for supporting and driving said blade, a gear drive for positively rotating said mount, means on said mount for frictionally gripping said disk to permit slipping of the blade without injuring the gear drive when the blade meets an abnormal obstruction, said means including a collar on the mount located on one side of the blade and a dished radially slotted washer having a flat peripheral surface in 60 engagement with the opposite side of said

disk, and a device for clamping the hub of the washer to said mount.

5. A cigarette cutoff having in combination a revolving carrier, a disk blade, means rotatably mounting said blade on the carrier, of a gear drive for rotating said blade relative to the carrier, and a device carried by said means for frictionally gripping said disk blade for permitting the blade to slip without injury to the gear drive when the blade meets an obstruction.

In testimony whereof, I have signed my name to this specification.

ELBERON D. SMITH.
